UNITED STATES PATENT OFFICE.

GEORGE P. HAYNES, OF BROOKLYN, NEW YORK, ASSIGNOR TO TODD DRY DOCK ENGINEERING & REPAIR CORPORATION, OF BROOKLYN, NEW YORK.

LIQUID-FUEL-DELIVERY APPARATUS.

Application filed January 21, 1926. Serial No. 82,873.

In apparatus for delivering liquid fuel, whether for flame production in furnaces and heaters, or for use in internal combustion engines, it is very desirable that provision be made whereby the quantity of liquid fuel delivered may be regulated within wide ranges to suit consumption needs, while maintaining efficient atomization.

Under existing methods of delivery the quantity of liquid fuel atomized can be varied only within a relatively limited range by reducing the pressure at which the fuel is supplied to the atomizer, because at too low a pressure atomization will be imperfect.

It is present day practice to equip atomizers with nozzles having delivery orifices of sizes best proportioned to the service for which they are intended, but no satisfactory provision is made for increasing the supply delivery range, without change of parts, to suit the great flexibility in load requirements found in certain classes of service.

Therefore, my present invention was conceived for the purpose of providing a liquid fuel supply delivery apparatus whose flexibility comprehends the requirements of all practical load variations, without necessitating any change in the equipment employed.

With these objects in view my improved delivery apparatus is embodied in a structure having an atomizing orifice for delivery of a main supply of liquid fuel, and a smaller sized atomizing orifice rearwardly spaced from the main orifice for delivery of a secondary supply of liquid fuel, both orifices being arranged along the same longitudinal axis, and each being having separate independent means of communication, to the end that supplies of liquid fuel under different pressures may be directed to the respective orifices.

Other features and advantages of my invention will hereinafter appear.

In the drawings:—

Figure 1 is a side sectional view of my improved delivery apparatus for liquid fuel, provided with separate atomizing means each having its own independent supply conduit.

Fig. 2 is a section on the line 2—2 of Fig.

1.

Fig. 3 is a section on the line 3—3 of Fig. 1.

Fig. 4 is an enlarged sectional detail view taken along a broken line, of the nozzle elements in their assembled form.

Fig. 5 is a face view of the intermediary plate having the secondary atomizer orifice and the collecting recess for liquid fuel passing to the main atomizing orifice.

Fig. 6 is a face view of the rearward nozzle element provided with means of communication to the intermediary plate.

Fig. 7 is a rear view of the rearward nozzle element, and

Fig. 8 is a side section of said rearward nozzle element, taken on the line 8—8 of Fig. 6.

The delivery apparatus includes the usual air supply tube 1, which engages at its rear end with the housing 2 and has the deflector 3 provided at its forward end. An inner tube 4, in spaced relation within tube 1, engages at its rear end with the coupling member 5, and at its forward end has an atomizer assemblage. The structure thus far described is substantially according to usual practice in the Todd type of burner, the tube 4 serving as a duct to convey liquid fuel to the atomizer. Since, however, my invention comprehends the provision of two separate supplies of liquid fuel to the atomizer, I place another or central tube 6 in spaced relation within tube 4, said tube 6 having separate means of engagement with coupling member 5. The tube 4 is of larger capacity than tube 6 and is termed by me the main supply tube, and the central tube 6 I call the secondary supply tube.

The nozzle structure comprises a rearward element, an intermediary element and a forward circular plate or tip 7 provided with an atomizing orifice 8 for delivery of the main fuel supply. The rearward element consists of a tubular neck portion 9 that fits over the reduced end 10 of tube 6 and is provided with a circular front closure formation 11 of larger diameter than tubular portion 9, the enlargement taking the form of a radial flange 12, that is pierced with a series of apertures 13. Also formation 11 has a concentric groove 14 depressed in its face in communication with apertures 13. The intermediary element consists of a disk 15 provided with a circumferential flange 16 that projects beyond both surfaces

of disk 15, so that said flange may encircle the closure formation 11 at one side of disk 15, and may also encircle the atomizer plate 7 at the other side of said disk in the assembled relation of the elements. The respective surfaces of disk 15 are identified by the letters *a*, *b* for convenience of reference. Surface *a* lies flatly against the face of formation 11, thereby affording front closure means for groove 14, excepting that apertures 17, through disk 15, are in communication with groove 14. The apertures 17 are arranged in a circle co-incident to the circular arrangement of apertures 13, but are less in number to restrict outgo from closed groove 14, as a step in the operation of breaking up the fuel.

A central recess 18 is formed in face *b* of disk 15, serving as a pocket or chamber to receive the liquid fuel, which enters said recess by way of slits 19 extended tangentially between the apertures 17 and the peripheral wall of the recess, the liquid fuel being thus caused to whirl within recess 18 preparatory to its exit through the atomizing orifice 8 of forward plate 7. The course provided through apertures 13, groove 14, apertures 17, slits 19, and chamber 18 to orifice 8 in plate 7 is that taken by the main supply of liquid fuel conveyed by tube 4.

Also the closure formation 11 is pierced with apertures 20, smaller than apertures 13 and extending from the interior of tube portion 9 to the face of formation 11, where they communicate, by means of tangential slits 21 with a central pocket or chamber 22 recessed in said formation 11, said pocket or chamber 22 being closed by the surface *a* of disk 15, excepting for a central atomizing orifice 23 therethrough, of smaller diameter than orifice 8, with which it is aligned for its discharge through plate 7.

The orifice 23 is so proportioned with respect to orifice 8 and so spaced therefrom that the atomized discharge from orifice 23 will approximately clear orifice 8.

The course provided through apertures 20, slits 21 and chamber 22 to orifice 23 is that taken by the secondary supply of liquid fuel conveyed by tube 6.

The assemblage of atomizer elements thus described is connected with the supply tubes, to form a part of the delivery apparatus, in the following manner:

Threaded upon the forward end of the main liquid fuel supply tube 4 is an angular nut 24, here shown as rectangular and fitted within air supply tube 1, leaving clearances 25 for the flow of air, said nut having a forward tubular portion 26, exteriorly threaded for engagement by an annular interiorly threaded cap 27, that is provided with an inturned flange 28. As will be observed in Fig. 1, the atomizer elements lie between the end of tubular portion 26 and

the flange 28, and are clamped securely in place by screwing the cap tightly upon tubular portion 26.

The coupling member 5, which is secured in operative position against bushing 29 by housing screw 30 is here shown as provided with the separate chambers 31, 32; tube 4 opening into chamber 31, and tube 6 fitting into a central aperture 33, through coupling 5, which aperture opens into chamber 32. A passage 34 extends outwardly from chamber 31 through the coupling member into communication with a passage 35 in the bushing, and connection is made with said passage by a supply pipe 36. Similarly, a passage 37 extends outwardly from chamber 32 through the coupling member into communication with a passage 38 in the bushing and connection is made therewith by a supply pipe 39.

Now it will be apparent that when only a relatively small flame is required to issue from the burner the main supply of liquid fuel, passing through tube 4 to the larger atomizing orifice 8, may be shut off entirely, leaving only the secondary supply open to tube 6, for delivery through the smaller atomizer orifice 23. It must be noted that the main and secondary atomizing and delivery means are entirely separate and distinct from each other, although included in the same apparatus; and that said supplies can be delivered separately.

Ordinarily under service conditions the main supply will be in use and the secondary supply shut off. But when less heat is to be generated the auxiliary supply will be turned on and the main supply shut off. As either supply may be turned on before shutting off the other there need be no flame extinguishment in effecting the change over.

Variations within the spirit and scope of my invention are equally comprehended by the foregoing disclosure.

I claim:

1. A delivery apparatus for liquid fuel provided with a pair of atomizing nozzle members in longitudinally spaced relation, said members respectively including axially aligned discharge orifices of different cross-sectional area, the smaller orifice being located rearwardly of the larger orifice, and separate liquid fuel supply means for each orifice operable respectively for main and secondary liquid fuel supplies under different pressures, the spaced relation between the nozzle members being such as to permit the atomized discharge from the smaller orifice to approximately clear the larger orifice.

2. A delivery apparatus for liquid fuel provided with a pair of atomizing nozzle members in longitudinally spaced relation, said members respectively including axially aligned discharge orifices of different cross-sectional area, the smaller orifice being lo-

cated rearwardly of the larger orifice, whirling chambers anterior said nozzle members respectively and separate liquid fuel supply means for each chamber operable respectively for main and secondary liquid fuel supplies under different pressures, the spaced relation between the nozzle members being such as to permit the atomized discharge from the smaller orifice to approximately 10 clear the larger orifice.

3. A delivery apparatus for liquid fuel provided with a pair of nozzle members in spaced relation, said members respectively provided with axially aligned discharge orifices of different cross-sectional area, the smaller orifice being located rearwardly of the larger orifice, whirling chambers anterior said nozzle members respectively, tangential inlet means respectively for said chambers, 15 and separate liquid fuel supply means for the respective inlet means operable respectively for main and secondary liquid fuel supplies under different pressures, the spaced relation between the nozzle members and the 20 relative size of said orifices being such as to permit individual atomization of the respective liquid fuel supplies.

4. A delivery apparatus for liquid fuel

having atomizing means which include a tip plate having an emission orifice, an intermediary disk lying rearwardly against said plate and having a recessed chamber, means of communication through said disk into said chamber, a rearward disk lying against said intermediary disk, said rearward disk 30 having a grooved chamber and means communicating therewith to coact with the communicating means through the intermediary disk, a tubular neck portion extended rearwardly from said rearward disk, said intermediary disk provided with an emission orifice smaller than the orifice in the tip plate and in axial alignment therewith, said rearward disk having a chamber recessed in its forward face, and having means of communication therewith, and said tubular neck portion provided with means of communication with said last named communicating means, a liquid fuel conveying tube, connecting means between said tube and the means 35 of communication through said rearward disk, and a second conveying tube which connects with said tubular neck portion.

Executed this 14 day of January, 1926.

GEORGE P. HAYNES.
